UNITED STATES PATENT OFFICE.

SAMUEL B. SHEEDON, OF DULUTH, MINNESOTA.

TAR-DRAG.

1,168,570.

Specification of Letters Patent. Patented Jan. 18, 1916.

Application filed April 1, 1915. Serial No. 18,535.

To all whom it may concern:

Be it known that I, SAMUEL B. SHELDON, a citizen of the United States, and resident of Duluth, in the county of St. Louis and State of Minnesota, have invented certain new and useful Improvements in Tar-Drags, of which the following is a specification.

My invention relates to by-product coke ovens and has particular reference to a novel means for preventing the accumulation of heavy tar in the mains leading from the ovens.

In the operation of by-product coke ovens the gas first liberated from the coal contains a quantity of tar and heavy hydrocarbons. The gas is collected in mains located over the ovens and a large proportion of the tar condenses and accumulates in the bottom of the main and is drawn off by suitable means.

20 In practice a heavy pitch gathers in the main which is very difficult to remove and which will cause obstruction if allowed to remain. Poke-holes have been provided through which bars or "spoons" can be inserted to prevent this accumulation and obstruction. This is a laborious and inefficient means for overcoming the trouble.

An object in the present invention is to provide a drag or scraper which shall be 30 adapted to be reciprocated slowly from end to end of a gas main whereby to prevent the accumulation of the pitch referred to and cause it to pass away with the more fluid tar. This pitch is a very tough substance and tends to adhere tenaciously to the bottom of the mains; therefore a drag for loosening this substance must be heavy and strong and be operated with sufficient force to cause it to thoroughly scrape the main 40 from end to end.

The invention will be more readily understood by reference to the accompanying drawings, wherein,

Figure 1 is a longitudinal section through the mechanism located at one end of a gas main; Fig. 2 is a similar view showing the opposite end of the main, and, Fig. 3 is a section on the line 3-3 of Fig. 1.

In the drawings a gas main is indicated 50 at 10. At one end of the main, as shown in Fig. 1, I mount a trough 11, which acts as a tar well or seal for the end of the gas main, which end is partially closed by the removable cover 12, leaving a space 13, 55 therebeneath, through which the tar drag

may extend. Mounted in suitable bearings in a casing above the trough 11, are a pair of drums 14, 15, both of which are shown as driven through the medium of a pinion 16, connected by suitable gearing to a motor 17. A driving cable 18, passes over the drums 14, 15, and around a pair of idlers 19, loosely mounted on a shaft 20, these idlers of course rotating in opposite directions. Mounted on the bottom of the main 10, is a flanged guiding member 21, as best shown in Fig. 3, the flanges 22, of which serve to retain in place and guide a drag 23. One end of the cable 18, is attached to the drag at 24, the cable thence passing around one of the idlers 19, the driving drums, then returning around the second idler and extending along the bottom of the main in the channel of the member 21, the portion of the cable thus utilized being indicated at 25, in Fig. 3. This cable 25, is shown in Fig. 2, as extending around an idler 26, thence underneath a second idler 27, and connecting with the drag. The means for connecting the cable to the drag may consist in the hook 28, which coöperates with a recess 29, in the drag, a lip 30, on the hook underlying a portion of the metal of the drag and preventing the removal of the hook while under tension. As a means for maintaining the cable under proper tension, I mount the idler 26, for oscillation on a shaft 31, and suitably connected with the idler is a spring 32. This end of the gas main is substantially a duplication of that shown in Fig. 1.

Mounted at the limit of the travel of the drag at either end of the main is a lever 33, having a counter-weight 34, therein, this lever being connected to any suitable reversing mechanism whereby the direction of movement of the prime mover may be changed. In the case of the motor shown the shaft of the lever 33, will be connected to a reversing switch. In the case of a steam engine of course the shaft will be connected to a reversing valve.

In operation the trough 11, and the lower part of the main 10, will contain tar to substantially the height indicated by the line 35, thus sealing the main against the escape of gas. The motor being started in operation, the drag 23, will be caused to move slowly from end to end of the main, the direction of movement being reversed when 110

the drag reaches the end and contacts one of the arms 33. The guide formed in the bottom of the main rigidly holds the drag in proper relation and at the same time provides for the return of the cable which may by this means be made endless instead of being wound upon a drum at each end of the main. The installation shown is simplified and it will be understood that in practice the same driving mechanism may be employed for dragging two or more adjacent gas mains by interconnecting the cables from the driving shafts.

I claim:

- 15 1. In a device of the class described, the combination of a gas main, an angular guide rigidly secured to the interior of said main, a drag adapted to be guided and limited in vertical and lateral movement thereby, 20 and means for moving said drag and reversing the direction of movement thereof, substantially as described.
- 25 2. In a device of the class described, the combination of a gas main having a curved lower wall, an angular guide extending from end to end of the main, a drag, the lower portion of which is shaped to correspond to the shape of the lower wall of the main, said drag being guided and limited in 30 vertical and lateral movement by said an-

gular member, and means for reciprocating said drag, substantially as described.

3. In a device of the class described, the combination of a gas main having partially open ends, tar seals provided for said partially open ends, a tar drag reciprocable in said main, an angular guide adapted to limit the vertical and lateral movement of the drag and an endless element connected to said drag and a prime mover and adapted to cause the reciprocation of said drag, substantially as described.

4. In a device of the class described, the combination of a gas main, a guiding member providing an open space therein, a tar drag reciprocable on said guiding member, said drag being limited in its movement and caused to travel in a substantially fixed path by coöperation with said guiding member, and an endless cable connected to said drag, the return portion of said cable occupying the space in said guiding member, substantially as described.

Signed at Duluth, St. Louis county, Minnesota, this 29 day of Mch., 1915.

SAMUEL B. SHELDON.
